GENERATION OF TONES IN PHOTOELECTRIC MUSICAL INSTRUMENTS

Edward M. Jones, Cincinnati, Ohio, assignor to
The Baldwin Company, Cincinnati, Ohio, a
corporation of Ohio

Application August 5, 1946, Serial No. 688,576

15 Claims. (CL. 250—41.5)

1 My invention relates to electrical musical instruments in which tones may be selectively generated and reproduced in accordance with the requirements of a musical score; and in particular it relates to that type of musical instrument wherein one or more beams of light are interrupted or modified in a periodic fashion and then impinged upon a photocell whereby the pulsations in the beam or beams of light are converted into electrical pulsations which may be amplified and reproduced.

Electrical musical instruments of this general class have hitherto been suggested. In one such instrument a succession of light beams is produced by causing light from a suitable source to be interrupted by alternate opaque and transparent portions of a rotating disk. The light beams are caused successively to traverse a portion of a photoelectric cell, the arrangement being such that as soon as one beam leaves the traversed area, another begins its traverse. The light beams are caused also to traverse a wave pattern screen of variable translucency on their way to the photoelectric cell so that the derived electrical pulsations will be characterized by a fundamental frequency and various harmonic frequencies in desired proportions to produce a selected voice or timbre. By changing the wave pattern screens, various voices may be obtained.

A principal object of this invention is the provision of means for producing tones having valuable characteristics beyond a bare content of fundamental and selected harmonics in selected proportions. Hitherto, all such frequencies have been constant during the continuous and constant-volume sounding of any given tone. The bare characteristics of constant fundamental and harmonic frequencies just set forth, will provide tones having voices or timbres which may be made imitative of the voices of known musical instruments, or may constitute new voices. But such tones are relatively cold and mechanical in character and lack something of the effect of the tones of an orchestral rendition, or even of any one instrument played by human agency.

When musical instruments are playing together in unison or in octaves, the sound can be accurately represented by a series of wave forms in a graph or chart. Successive wave forms will be nearly the same; but they will not be identical. The change usually occurs at a rate which is comparatively slow compared with the audio rate of the vibrations themselves.

2 For example, when a group of violins are played in unison, not only are there slight differences in the specific frequencies of the fundamentals and harmonics produced by each, but each violin may have its individual vibrato.

It is an object of my invention to provide means and methods whereby photoelectrically generated wave forms may be given similar characteristics. It is an object of my invention 10 to provide means and methods whereby the generated wave forms may be caused to pass through a sequence which repeats continuously every few seconds or a sequence which is initiated when desired, as when a key is depressed, or both.

These and other objects of my invention which will be set forth hereinafter or will be apparent to one skilled in the art upon reading these specifications, I accomplish by that construction and arrangement of parts and in those procedures of which I shall now describe exemplary embodiments.

Reference is made to the accompanying drawings wherein:

25 Figures 1 to 6 inclusive are representations of wave forms to which I shall refer to illustrate results of the practice of my invention.

Figure 7 is a diagrammatic representation of elements of a photoelectric instrument to which 30 my invention may be applied.

Figure 8 is a diagrammatic representation of an interrupter and a wave form screen.

Figures 9 and 10 and 11 represent various embodiments of wave form screens.

35 Figure 12 is a diagrammatic representation of yet another form of interrupter.

Figures 13, 14, 15, 16 and 17 are diagrammatic representations of still other forms of interrupter and screen mechanisms, Figure 15a 40 showing a wave form screen for percussive effects.

In Figure 7, I have shown in a purely diagrammatic fashion the operating elements of a photoelectric device such as those to which my 45 invention, as later described, may be applied. Light from a source 1 is broken into a series of traveling beams by slots 2 in a disc 3 which rotates at a fixed speed. The beams, condensed as may be required by a lens system 4, traverse 50 a photocell 5. A shutter, having a fixed element 6 with a window, and a movable element 7, connected by some means 8 to a playing key 9, serves the dual function of permitting the beams to pass when the particular note is desired, and 55 of confining the beams in such fashion that as

soon as one beam completes its traverse another begins to traverse the photocell.

The light source 1 may be controlled by a stop 10 through a switch 11. The photocell will be connected through an amplifier 12 to a loud-speaker 13 for the production of sound.

On their way to the photocell, the beams of light pass through a wave-form screen 14 with portions of varying opacity, or transparent portions of varying area, the purpose of which is to cause the beams to change in intensity, during their traverse, in accordance with a predetermined wave form or pattern. In this way, the electrical pulsations produced in the photocell may be made to have a "voice" comprising desired harmonics in desired intensities, in addition to the fundamental. Since, as pointed out, the beams in continuous sequence traverse the photocell, it will be evident that the wave pattern is constant, i. e., repeated over and over again at a constant frequency, and can be represented on a chart or graph.

Figure 7 is, as indicated, diagrammatic. A practical instrument would involve one or more of the interrupter discs, each having many circles of slots, aggregating one circle for each of the notes within the range of the instrument. Further multiplication of parts may be made if the instrument has more than one manual. There may be a separate wave form screen for each desired tone quality at each pitch, although it will be evident that wave form screens for a plurality of notes and voices may be mounted on the same supporting means. There may be a separate light (and photocell means) if desired, for each tone quality, or means may be provided to shift different wave forms screens into position as required. The wave form screens may be, for example, variable density patterns on a photographic plate, and the sound may be made to build up and decay in accordance with movements of the shutter by special shutter construction.

The specific construction of the instrument in which the invention I am about to describe is embodied, is not limitative upon the invention itself, and may be widely varied. The principles of my invention are applicable generally to devices in which beams of light are caused to impinge upon a photocell in succession at a desired fundamental frequency, and during such impingement are modified in such fashion as to provide harmonics. In the exemplary embodiment a point source of light is desirable so that sharp shadow images of the slots can be cast on the wave form screens. The ability of such a system to reproduce the higher harmonics of a tone depends upon the narrowness of the beams of light passing across the wave form, which in turn depends on the width of the slots, the size of the light source, and the distance between the slots and the wave form. If the light source is very concentrated, diffraction effects may predominate, in which event better results may be obtained if the spacing between the slots and the wave form is increased. If the light source cannot be made concentrated enough, images of the disc slots can be projected onto the wave form screens by a lens system.

Turning to Figures 1 to 6, let us assume that the tone produced by the apparatus shown in Figure 7 contains three frequencies of 100, 200 and 300 cycles respectively, the last two of which are harmonics of the first. This may be represented graphically as in Figure 1 as a musical

tone 15 of constant timbre. Such a tone would not normally be produced excepting by purely mechanical or mechano-electrical means. When an instrument is played by human agency 5 there are usually slight variations in timbre which impart variety and interest. Similarly, when a group of violins play in unison, for example, they are not all exactly in tune, and each has its own pitch-tremolo. Moreover, most instruments have percussive effects having to do with the onset of the tones, variations in volume after the onset, and, frequently, variations of timbre.

In the practice of my invention I am able to 15 produce tones of varying timbre, which can be accurately represented as a series of wave forms, successive ones being nearly the same, but exhibiting a change occurring at a slow rate compared with the frequency of the tones. I can cause my wave forms to pass through sequences 20 which may be classified into various types. In type 1, the timbre variation repeats every few seconds. In type 2, the tone dies away within a few seconds, with or without timbre change. 25 Type 3 is essentially a combination; but it may be characterized by an initial sequence of wave forms followed by repetitive sequences.

Tones of the first type may be made to imitate 30 a group of instruments playing in unison. Tones of the second type are essentially percussive in nature. Tones of the third type could imitate for example, combinations of organ pipes, each having its own delay, manner of attack, initial timbre, and pitch, as well as steady timbre and pitch.

In Figure 2 I have illustrated graphically a 35 simple form of musical tone 16 of varying timbre of type 1 above. In this particular case, the waveform sequence repeats twice a second, so a 40 curve showing what happens in a half-second interval is sufficient to define the tone. Around $t=0$ and $t=.5$ second, the wave is like the one shown in Fig. 1, but in the middle (at $t=.25$), the wave is entirely different. Notice, however, that 45 the curves for successive $\frac{1}{100}$ sec. intervals do not differ much, which means that one can call the sound essentially a 100 cycle sound. In the equation for the curve, one will notice frequencies of 100, 102, 196, 200, 204, 296, 298, 300, 302, 304 50 cycles per second. (The Fourier theorem requires that the frequencies be spaced 2 cycles apart because of the fact that the wave repeats twice a second.) These frequencies may be put into 3 groups, those close to 100 cycles, those close to 200 cycles, and those close to 300 cycles.

These three groups of frequencies are plotted 55 separately in Figs. 3, 4 and 5 at 17, 18 and 19. Notice that the curves in these figures look like sine waves. The slow changes in phase and amplitude of these sine waves during the half-second interval may be considered to be the results of beats between the various steady sine wave components. Another way of looking at these varying sine waves is that each cycle of the wave in Fig. 2 may be analyzed by Fourier analysis into 1st, 2nd and 3rd harmonics, and since the waveform is slowly changing, the magnitude and phase angle of each harmonic will change from cycle to cycle.

Three basic phenomena that occur when steady 70 sine waves of nearly the same frequency combine are illustrated by the curves of the three harmonics. The curve 17 in Fig. 3 is a typical result of combining two sine waves of slightly different frequencies. At the ends of the curve,

the magnitude of the resulting sine wave is largest because the two components are in phase or add. In the middle of the curve, there is minimum amplitude because the two components are out of phase, or subtract from one another. Notice that at $t=.2$ and $t=.3$ second, the peaks of the waves do not occur exactly at the same places relative to the $\frac{1}{100}$ sec. marks, which means the phase angle of the sine wave is changing. This little fact prevents the wave from being considered merely as a 100 cycle wave the magnitude of which is changing.

The curve 18 in Fig. 4 is made up of three sine wave components; but it happens that in this case the principal effect lies in phase changes, instead of magnitude changes in the resulting sine waves. It takes a close examination of the curve to detect the phase changes and to see that the peaks do shift back and forth relative to the $\frac{1}{100}$ second marks. The ear, however, will easily detect the vibrato, or shift in pitch up and down 4 times a second (which is equivalent to the phase varying 4 times a second).

Figure 5 shows in curve 19 the third harmonics which happen to be undergoing changes in magnitude, but are constant in phase. This is because the component frequencies are equally distributed above and below 300 cycles. Those familiar with amplitude modulation in radio will recognize that the wave is equivalent to a 300 cycle carrier modulated with frequencies of 2 and 4 cycles, producing side bands of 296, 298, 302, and 304 cycles.

To sum up it may be said that a type 1 tone as defined above consists of a fundamental and various harmonic sine waves, each of which is periodically undergoing separate changes in magnitude and frequency or phase.

Fig. 6 shows a type 2 or percussion type tone in curve 20. Unlike the curves in the foregoing figures, it does not repeat after $t=.5$ second, but instead, the 100 cycle wave that is still present at the end of the curve dies out in another second or so. The equation for the curve shown barely scratches the surface of the many possibilities for tones, but it does show some principal characteristics of percussion sounds. Note that the 100 cycle component takes a few cycles to build up to its maximum value, and then dies out more slowly than the other harmonics. The second and third harmonics predominate at first, as seen by the initially complicated wave-form. Though the second and third harmonics decay at the same rate, and neglecting the fundamental, the wave-form would still be changing because the third harmonic, having a frequency of 304.3 cycles, is not a true harmonic. Notice that type 2 tones can contain decaying sine waves of any decimal frequency as long as it is not too different from a true harmonic.

Taking up first my methods and means for securing the type 1 variation, which is the simplest form of variation here involved, I have illustrated in Fig. 8, a rotating disc 21 which, instead of having concentric circles of slots for each pitch is provided with a series of perforations 22 arranged in a spiral configuration. Each of these perforations therefore will scan a slightly different part of an elongated wave form screen 23. It will be evident that the perforations move transversely across the screen, which not only is of variable density transversely to impart the desired harmonics, but also changes progressively in the opposite or longitudinal direction.

The waveform 24 shown in Fig. 9 is an actual

representation of the variable density pattern necessary to produce the tone in Fig. 2 (assuming the shaft 25, Fig. 8, runs 2 revolutions per second). The time at which each portion of the wave form is used is shown, and it should be noticed that the waveform extends above and below the portion actually used (between $t=0$ and $t=.5$ sec.) The extended portions are repeated parts; but they insure that the tone quality will not be affected appreciably if the waveform is slightly out of position with respect to the disk.

Fig. 10 shows a waveform 26 for a single frequency, a 406 cycle sine wave. It can be seen that there would exist a waveform for any frequency which is a multiple of the frequency of rotation of the disk (which in this case is 2 cycles per second). To reproduce the waveform efficiently, the holes in the disk must be smaller than the distance between the slanting ridges on the pattern. This means, roughly, that one cycle of the harmonic (the 4th in the above case), plotted in the horizontal direction, must be larger than the hole; and the distance traversed in the vertical direction during one (hypothetical) beat between the frequency in question and the pure harmonic (400 cycles) must be larger than the holes. In the example given, these conditions are met, because the holes are smaller than $\frac{1}{4}$ of the horizontal length of the waveform and smaller than $\frac{1}{3}$ of the vertical depth of the waveform. It can be seen then that the system is incapable of reproducing well frequencies above certain value and differing more than a certain amount from the true harmonics (multiples of 100 cycles in this case). These limitations may be considered as an advantage, since it means that imperfect waveforms do not produce much dissonance.

Any waveform used in the spiral scan method of Fig. 8 may be considered to be a combination of many waveforms like the one shown in Fig. 10. In making waveforms, it is preferred to synthesize them out of single frequency waveforms, after having emphasized those frequencies that reproduce poorly because of the size of the holes on the disk.

Fig. 11 shows a waveform 27 that produces the vibrato tone, the waveform of which is shown in Fig. 4 at 13. This tone is one of the components of the tone of Fig. 2, and a visual comparison between the waveform 24 of Fig. 9 and the one in Fig. 11 shows some resemblance.

In the use of complex waveform screens such as those illustrated at 24 in Fig. 9 and 27 in Fig. 10, the holes in the disc do not need to be limited in diameter to the depth of the representation of any particular cycle on the screen. On the contrary, if some lapping occurs, a smoother variation is produced.

While as indicated above, the principles of this invention may be incorporated in instruments of widely varying design and characteristics, a consideration of certain features of an exemplary embodiment contribute to an understanding of the principles.

A practical instrument based on the principle of Fig. 8 may be made as follows: A photographic disk rotating $\frac{2}{3}$ revolution per second has 73 concentric spirals of holes .002" in diameter. (This means the waveform sequences would repeat once every $1\frac{1}{2}$ seconds.) The spirals may be spaced .070" apart and the total variation of radius of each spiral would be .050". The inner spiral would have an average radius of 1" with 49 holes for the lowest C in a "16 foot" tone. The outer spiral would have an average

radius of 6.04" with 3140 holes to produce the highest C for 8 or 4 foot stops. Each waveform, instead of being just 1 cycle long as in Fig. 9, would contain from 3 to 30 cycles, which means that an imperfection in one of the holes in the disk would cause much less disturbance. The waveforms may be arranged in two radial rows, with the shutter apertures alternating from one side to the other, so that each waveform could have a width of .12" of which .05" was used. The waveform for one stop may be photographed on a strip of film 1 x 6" and despite dimensional instability of the film, the spirals would still pass over the waveforms.

The shutters are preferably arranged to let light onto the whole area traversed by the spiral gradually as the key is depressed, in order to produce a smooth rise and decay of the tone, under the control of the performer.

Arrangements to have combinations of two or more waveforms acting when one key is pressed, of course, add to the versatility of the instrument and make it like an organ; but there is also the possibility of producing binaural effects by putting the light from two different wave forms into separate photocells, amplifiers, and speakers, which could give the effect of instruments or pipes located in different places playing in unison (or octaves). The application of this method of producing binaural effects on type 2 and type 3 sounds discussed below might be still more effective.

In Figure 12 I have shown a waveform screen 28 in combination with two slotted discs. The disc 29 is provided with a series of slots 30, which, co-acting with the slots 31 of the disc 32 give a scanning effect when these discs are rotated in proper speed ratios on their respective shafts 33 and 34.

The method and means of Fig. 12 produces type 1 tones, and has the advantage that the pitch disk 32 need not run as slowly as the one discussed above to prevent too frequent repetition of the waveform sequence. The same type of waveform is used. If the shaft 33 of the auxiliary disk 29 runs at such a speed to cause one slot 30 to pass the stationary waveform every half second, and the shaft 34 of the pitch disk rotates every half-second, then the wave of Fig. 2 will be reproduced. However, there is no reason why the auxiliary disk could not run much slower than this to produce a waveform sequence repeating say every 2 seconds, while the pitch disk 32 could run 4 times a second, which would give good high frequency response. Furthermore any deviations from the tempered scale resulting from having to choose an integral number of slots on the pitch disk 32, which might be plus or minus 2 cycles, could be corrected in the waveform to an accuracy of plus or minus $\frac{1}{2}$ cycle.

In a practical instrument, it might be best to have the scale split up onto two pitch disks, the ones with the high pitches running much faster. There are many ways of arranging the auxiliary disk, and the same circle of slots on the auxiliary disk may be used for many circles on the pitch disk. There is no necessity that the disks move across the wave forms exactly at right angles. While I have illustrated a disk 29 as having the slots 30, it will be understood that these slots may be located on another member, e. g. a band, running radially of disc 32.

In Fig. 13, I have shown a pitch disc 35 having a series of slots 36 for a particular frequency. Above it, and mounted rotatably on the same

shaft 37 or on a sleeve on that shaft, I have provided another disc 38, characterized by radial slots 39, having a width which is the same as the circumferential distance between the radial slots 36 in the disc 35. The tone screen 40 carries a sequential representation 41 of a series of wave forms of differing characteristics. Each represented cycle has a length approximately equal to the width of a slot 39 at the same radial position, and the total length of the representation 41 is at least equal to the circumferential distance between slots 39 at the same radial position.

Fig. 13 shows a method and means by which type 1 tones can be produced without using a two dimensional waveform. In this case the pitch disc 35 and the auxiliary disc 38 run concentrically as indicated, and the variable area plot 41 is made of a sequence of ten wave forms. In this particular case, where it was desired to reproduce the tone of Fig. 2, every fifth cycle of the curve of Fig. 2 is plotted in succession, and the pitch disc runs twice a second, while the auxiliary disc 38 turns once every $2\frac{1}{2}$ seconds. This means that during a half second interval, a slot 39 on the auxiliary disc 38 passes across the succession of waveforms, and since this slot is one cycle wide, there is always one narrow slot exposed on the pitch disc 35. This slot is passing across the waveform at the correct speed; and the wave form is changing in approximately the correct way.

The speeds of the auxiliary and pitch discs can be made to obtain the same advantages as to accuracy of pitch and high frequency response as in the two disc method of Fig. 12, but here it is still more desirable to split the scale between two pitch discs going at different speeds. Otherwise, the low notes would require waveforms clear around a circle. The method can be used with variable density waveforms, and by operating the shutter in radial direction, and varying the density pattern in the radial direction, the tone quality can be made to change in any desired manner as the key on the keyboard is slowly depressed. The waveform is therefore made to be essentially a three dimensional pattern.

The successive waveform method of Fig. 13 has some serious disadvantages, however. In the first place, a large area has to be illuminated very evenly, and the dimensional and density stability of the waveforms has to be good to prevent a poor transition as a new slot 39 enters the waveform. In the second place, the method inherently distorts instead of simply attenuating frequencies that differ appreciably from the pure harmonic frequencies. Distortion occurs every time a transition is made from one slot to another on the pitch disc 35; and the amount of distortion depends upon the jump between two successive waveforms. By making blurred variable density instead of sharp edges on the slots 39 of the auxiliary disc, so that a blurred shadow is cast, the transition from one slot to another on the pitch disc may be made very smooth, and distortion will be much reduced.

Certain of these disadvantages may be obviated by eliminating the disc 38 and placing the waveform representations 41 concentrically on a disc which is itself concentric with the disc 35. The waveform representations may vary progressively or repetitively throughout an entire circle. In this form, the waveform screen rotates; but the window of the shutter member 6 or its equivalent is used to confine the beams to the proper scanning area. It will be evident that if the full circumference of a disc bearing the wave patterns

is used in this fashion, a different pitch disc and appurtenances must be used for each desired voice.

In Fig. 14, I have shown a pitch disc 42 rotating on a shaft 43 and having a series of perforations 44 arranged circularly rather than spirally. The waveform screen or screens 45 may be arranged on a suitably guided member 46 which is moved back and forth radially of the disc 42 by a cam 47.

The back and forth method of Fig. 14 can reproduce only a restricted class of type 1 tones; but it has merits of simplicity and reliability that make it worth while. The system uses a variable density waveform screen similar to the kind used in the spiral scan method of Fig. 3. The waveform moves back and forth, maintaining a constant speed during most of each half cycle by means of the cam. Since the motion of the waveform screen is back and forth, the sequence of waveforms occurring during half a revolution of the cam must be repeated backwards during the next half revolution.

Mathematically this appears as follows: Let T be the total time for one revolution of the cam and let f_0 be the frequency with which the holes 44 pass across the waveform. The resulting wave will then be composed of continuous sine waves of various frequencies $kf_0 \pm n/T$, where n and k are integers. The restriction is that for every component of frequency $kf_0 \pm n/T$ there must exist a complementary component of frequency $kf_0 - n/T$ whose amplitude is the same, and which starts out in the same phase when the waveform screen is in one of the extreme positions. This restriction eliminates the possibility of producing tones that are better in tune than the frequency of the holes passing across the waveform; and inharmonic components of tones cannot be produced unless the pitches are distributed equally above and below this frequency. Vibratos and combinations of large numbers of instruments, however, can be imitated successfully.

In an actual instrument the various circles of holes can be spaced rather closely on the pitch disc, and by staggering the shutters into several rows, the waveform screens can still be made fairly large (radially). The waveforms for all the pitches can be moved back and forth by a single cam.

There are various ways in which percussive tones may be obtained in musical instruments. It has hitherto been suggested that the keys of an instrument be coupled to a control mechanism functioning for example to cause the volume of the reproduced tone to die away, or to cause the volume to follow a desired definite curve. In a photoelectric instrument, such effects might be obtained by means controlling the movement of the shutter mechanism, or the brightness of the light source. The application of such means to my instrument has the advantage that percussive effects may be obtained in tones of type 1 timbre variation, and devoid of the monotony usually characteristic of mechanically or electrically generated tones. However, in most percussive or choral instruments, a variation of timbre accompanies percussive variations in volume in a definite relationship. In my instrument this may be accomplished by coupling the wave form screens or the scanning devices or both to the keys or shutters so that a definite waveform sequence which starts from the beginning whenever a key is pressed may be obtained. Percussive variations of volume may be built into the waveform screen or may be attained otherwise, as by

controlling the movements of the shutter, the intensity of the light source, and the like.

Figs. 15 and 16 show a method and means for producing type 2 tones. When the key on the keyboard is pressed, a shutter diagrammatically indicated at 48 (Fig. 16) opens. A slot 49 in a member 50, starts moving across the wave form 51 at a slow rate (from left to right). The slots 52 on the disc 53 are continually moving across the wave form and they scan that part of the waveform exposed by the slot 49. The right hand side of the waveform is so dense that by the time the slot 49 has reached the right hand position, the light variations and the resulting tone have died out completely. When the key on the keyboard is lifted, the shutter closes and the slot 49 returns quickly to the left hand side of the waveform screen, whether or not its traverse has been completed.

The waveform 51 (Figure 15a) is representative of the waveform necessary to produce the sound shown in Figure 6. The most remarkable feature of this particular wave form is the appearance of some faint ridges slanting down toward the right, which is the effect of the inharmonic frequency of 304.3 cycles. It will be observed that this wave form is made darker on the right-hand side. In the previous wave forms, the transparency of the waveform at any point was made proportional to a constant plus the instantaneous value found at the corresponding point on the graph of the sound wave. For the percussion case, however, instead of adding a constant to the curve, the exponential function $140 e^{-3t}$ was added. Theoretically this hardly affects the tone, but practically it is important to bias the wave form to be very dark at the end, so that imperfections in the wave form will not produce a stray tone at the end.

A mechanical method of making the slot 49 pass slowly across the waveform is shown diagrammatically in Figure 16. When the key connected to the transmission means 54 is pressed, it opens the shutter 48 and puts tension on a spring 55, which draws upwardly a lever 56 pivoted at one end 57, and carrying a roller 58 at the other end. This roller presses a strip 59, which is connected to the member 50, against a shaft 60 which is rotating at a slow, constant rate. The strip 59 moves slowly to the right, carrying with it the member 50 which has the slot 49. The strip 59, in moving, stretches a spring 61, until a stop 62 is hit, by an abutment 63 on the strip. When the key is released, the shutter 48 closes and the roller 58 drops, no longer pressing against the strip 59. The spring 61 quickly pulls the strip 59 and the slotted member 50 back to the original position, as determined by a stop 64. Stop means 65, 66 and 67 are provided for the shutter.

The shutter 48 is arranged to open last and close first; and if the key is pressed down slowly, the loudest part of the waveform may be entirely bypassed by the time the shutter opens. This is the effect desired to imitate a piano, where the loudness depends on the speed of pressing the key. The effect could be improved by having the strip 59 initially make contact with a faster moving shaft.

The extreme versatility of this method for producing percussion tones can be appreciated when it is considered that any percussion tone can be recorded by pressing the key and modulating the light beam, as in the methods for recording on movie film. The tone will reproduce satisfac-

torily providing that the frequency of the percussive tone recorded was approximately synchronized to the frequency of the slots on the disc passing across the wave form, providing the harmonics were not too high or inharmonic, providing the tone died away soon enough, and providing the wave form or loudness did not change too rapidly.

With different wave form screens, different percussive effects may be obtained; and I am not limited to the particular one described in which the timbre and volume vary as shown in Fig. 6.

Various combinations and modifications may be made within the pervue of my teachings. One such variation lies in the production of the type 3 sequence mentioned above. In this sequence, the tones, when initially struck have a different timbre and (if desired) volume from that which they attain after a brief interval; but when the initial tonal effect is achieved, the note continues with a periodic or cyclical variation of timbre. These effects may be attained by providing a waveform screen with the initial effect at one end merging into the repetitive effect in the remainder of the screen, and by scanning the whole screen first and then the said remainder repetitively.

In Fig. 17 I have shown a pitch disc 68 having slots 69. A wave form screen 70 is provided of the type just described. A member 71 is operated in the same manner as the member 59 of Figs. 15 and 16, as by a rotating shaft 72, but is shown as moving transverse to the radius of the disc 68, and as provided with a series of diagonal scanning slots. The first of these slots, marked 73, is a slot of such length as to be capable of scanning the entire depth of the wave form screen 70. The wave form markings on the screen will, of course, be tilted to match the scanning direction which is substantially parallel to the slots assuming that these move slowly with respect to the pitch disc. Additional slots 74 are provided of lesser length and operating, as will now be clear, to confine the scanning to the lower portion only of the wave form screen. The slots 73 and 74 are so related as to their ends that as soon as one slot moves away from the window of the scanning screen (or such other window as is provided), the next enters it.

Tones produced in this fashion may have an initial timbre and/or volume, followed by a different timbre and/or volume, the latter being repetitive.

In such a system, the playing of the note may be prolonged for as long a time as it is feasible to keep the strip member 71 moving. Various mechanical embodiments of the principle may be made; but it is readily possible to provide in this way for type 3 effects with tones sustained as long as may be required for the usual musical composition.

It will be understood that the various teachings herein may be embodied in different mechanical constructions and may be combined. Thus in an instrument having a plurality of manuals, the percussive effects may be confined to one of them, allowing sostenuto effects to be obtained on another. Again, percussive effects may be confined to a particular voice on one manual.

Modifications may be made in my invention without departing from the spirit of it; but having outlined the principles of the invention in certain exemplary embodiments, what I claim as new and desire to secure by Letters Patent is:

1. In a photoelectric instrument, interrupting

means for imparting to a beam of light variations at a desired fundamental frequency and a wave form pattern for imparting thereto variations corresponding generally to harmonics of the fundamental, said wave form pattern having progressive variations thereon for producing changes in said last mentioned variations corresponding to minor shifts in the frequencies of said harmonics.

5 10. 2. In a photoelectric instrument, means providing a wave pattern to impart harmonic frequencies to an interrupted beam, said means comprising a wave form screen containing representations of more than one cycle of the wave, 15 said cycles differing from each other, and means for causing different parts of said wave form screen to modify said beam of light successively to generate a tone of varying timbre.

3. In a photoelectric device, interrupting 20 means for interrupting a beam of light, wave form means for modifying the interrupted beam to impart frequency variations which are harmonics of the frequency of interruption, said last mentioned means having a plurality of wave form modifying means in different parts and differing from each other, means for producing relative movement of the light beam and said modifying means in one direction to effect addition of said harmonics, and means for producing relative movement of the beam and the modifying means in another direction to produce variations in the harmonic additions.

4. In a photoelectric device, a wave form screen bearing a succession of wave form representations differing one from another in harmonic content, and scanning means for producing relative movement of a beam of light and said screen in such manner as to cause said beam of light to scan said representations successively.

35 5. The structure claimed in claim 4, wherein said wave form representations constitute a repeatable series and wherein said scanning means operates to scan said representations successively and repetitively.

40 6. In a device of the character described, a pitch disc having a series of light openings arranged spirally thereon in combination with a wave form screen carrying a succession of differing wave form representations which are scanned successively by said spirally arranged light openings.

55 7. In combination, a pair of discs rotating on different centers, one of said discs having a series of circumferentially arranged light slots, the other of said discs having a series of circumferentially arranged light slots crossing the path of the first mentioned series in one radial position, and a wave form screen, said arrangement of said slots causing a beam of light to scan said wave form screen progressively from one end to the other while said beam is moving transversely across said screen, said screen bearing representations of successive wave forms of different harmonic content in position to be so scanned.

60 8. In combination, a disc having a series of circumferentially arranged slots therein to interrupt a beam of light at a fundamental frequency, a wave form screen carrying a plurality of representations of cycles of the fundamental frequency differing as to harmonic content, and a scanning means interposed in the path of light including said first mentioned means for causing the beam of light to scan different parts of said wave screen successively.

13

9. In combination, a disc having a series of circumferentially arranged slots therein to interrupt a beam of light at a fundamental frequency, a wave form screen carrying a plurality of representations of cycles of the fundamental frequency differing as to harmonic content, and a scanning means interposed in the path of light including said first mentioned means for causing the beam of light to scan different parts of said wave screen successively, a playing key shutter, means in connection with said playing key to control said beam of light, driving means in connection with said playing key to initiate movement of said scanning means, and driving means effective upon release of said key for returning said scanning means to starting position.

10. The structure claimed in claim 9 in which said wave form screen embodies a general variation in density throughout said representations so as to effect a progressive variation in the intensity of said beam of light during said scanning.

11. The structure claimed in claim 8 wherein said scanning means operates to scan one portion of said wave form screen repetitively, and one portion thereof non-repetitively.

12. In a photoelectric instrument, having a source of light and a photocell, interrupting means for interrupting a beam from said source at a desired fundamental frequency, wave form means for imparting to the interrupted beam variations at frequencies responding to harmonics of said fundamental frequency, said wave form means having progressive variations therein for shifting the phase and varying the amplitude of

14

said harmonics, and scanning means for causing said beam to scan said variations successively and repetitively, to imitate the beats obtained from instruments played in unison.

5 13. In a photoelectric instrument having a light source and a photocell, interrupting means for interrupting a beam of light from said source at a desired fundamental frequency, wave form means to impart to the beam variations responding to 10 harmonics of said fundamental, and further wave form means for producing a progressive variation in the harmonic content of said beam.

14. In a photoelectric instrument having a light source and a photocell, interrupting means for interrupting a beam of light from said source at a desired fundamental frequency, wave form means to impart to the beam variations responding to harmonics of said fundamental, and further progressively varying wave form means for producing 20 a progressive variation in the harmonic content of said beam, and a progressive variation in its intensity.

15. In a photoelectric instrument having a light source and a photocell, interrupting means for 25 interrupting a beam from said source at a desired fundamental frequency, wave form means for producing in said beam variations responding to harmonics of said fundamental, and said wave form means having variations for progressively 30 changing the nature of said variations both as to the individual amplitude and frequency of said harmonics.

EDWARD M. JONES.

Certificate of Correction

Patent No. 2,439,392.

April 13, 1948.

EDWARD M. JONES

It is hereby certified that errors appear in the printed specification of the above numbered patent requiring correction as follows: Column 3, line 37, for the word "forms" read *form*; column 13, line 10, for "key shutter," read *key, shutter*; and that the said Letters Patent should be read with these corrections therein that the same may conform to the record of the case in the Patent Office.

Signed and sealed this 8th day of June, A. D. 1948.

[SEAL]

THOMAS F. MURPHY,
: Assistant Commissioner of Patents.
